CLAIM

I claim the ornamental design for portable cloth cutting table, as shown and described.

DESCRIPTION

FIG. 1 is a perspective view one of portable cloth cutting table, showing my new design;

FIG. 2 is a front elevational view thereof;

FIG. 3 is a bottom plan view thereof;

FIG. 4 is a top plan view thereof;

FIG. 5 is a rear elevational view thereof;

FIG. 6 is a left side view thereof; and,

FIG. 7 is a right side view thereof.

In the drawings, the broken lines show portions of the portable cloth cutting table that form no part of the claimed design.
